UNITED STATES PATENT OFFICE.

WILLIAM H. WHITE, OF ROANOKE, VIRGINIA, ASSIGNOR TO WHITE-AMERICAN LOCOMOTIVE SANDER COMPANY, INC., OF ROANOKE, VIRGINIA, A CORPORATION OF VIRGINIA.

SAND-TRAP.

1,164,899.

Specification of Letters Patent. Patented Dec. 21, 1915.

Application filed February 19, 1915. Serial No. 9,395.

To all whom it may concern:

Be it known that I, WILLIAM H. WHITE, a citizen of the United States, residing at Roanoke, in the county of Roanoke and 5 State of Virginia, have invented new and useful Improvements in Sand-Traps, of which the following is a specification.

This invention relates generally to an improvement in sanding devices for locomotives, and particularly to an element of 10 such devices known as the sand-trap, wherein in the sand is lodged by gravity from the source of supply, from which it is forced through the feed tube to the track, the present invention constituting an improvement 15 upon that shown in my prior Patent No. 1,117,119, dated Nov. 10, 1914.

The main object of the present invention is the provision of a sand-trap in which 20 the use of a nozzle having a check-valve or other elements liable to be clogged with sand is avoided, and in which a self-clearing nozzle of novel construction is employed.

A further object of the invention is the 25 provision of a trap in which the sand channel is so formed as to prevent the gravity feed of the sand therethrough, while at the same time affording little obstruction to the movement of the sand under the influence of 30 the air blast.

A further object of the invention is the provision of a nozzle which, in addition to being self-clearing, may be removed to permit the trap to be cleaned out, and which 35 is designed to direct the air blast in such a manner as to secure a positive feed of the sand, while avoiding an objectionable concentration and wearing action of the blast on the walls of the trap.

40 A further object of the invention is the utilization of an air blast operating through a portion of the trap and beyond the sand channel therein, which blast is utilized when necessary as a clean out medium for the feed tube beyond the trap, whereby said tube may be at all times maintained in effective condition for the proper movement of the sand therethrough in sanding the track.

45 50 A further object of the invention is to provide a nozzle having a blast passage of novel formation, serving as a means for temporarily collecting and retarding or prevent-

ing the backward feed of any sand particles which may lodge therein, and so that 55 under the influence of the blast such particles will be dislodged and forced into the blast chamber.

The invention consists of the features of construction, combination and arrangement 60 of parts herein fully described and claimed, reference being had to the accompanying drawing in which:—

Figure 1 is a vertical longitudinal section through a sand-trap embodying my invention. Fig. 2 is a similar view of the head-plug on an enlarged scale. Fig. 3 is a cross section on the line 3—3 of Fig. 2.

The improved trap, which aside from the details hereinafter described may be in any 70 form, preferably comprises a T-shaped body 1 having an upright section 2 designed for connection to a suitable pipe leading from the source of supply, and a lateral section 3, the terminal of which is designed to be 75 connected in any usual or preferred manner to the sanding or delivery tube 4 for the delivery of the material to the track. The body is interiorly and longitudinally cored to provide what I term a sand channel 5, 80 the formed wall of this channel from a point beyond the upright of the body to a point a slight distance from the outlet end of the body being on a curved or inclined plane, as at 6, the curved or inclined portion of the channel forming a trap to prevent the travel of the sand through the channel by gravity or under the jars to which the body is subjected in the travel of the engine. The body 1 at approximately 90 the juncture of the upright and lateral portions of the channel is cored and interiorly threaded at 7, and above the bore or opening 7 the upright portion 2 is provided with an interiorly threaded opening 8. 95 These openings 7 and 8 are designed to provide a means whereby the sand channel may be cleaned out by any suitable tools, when such may become necessary, the opening 7 also serving for the reception of the blast nozzle, while the opening 8 may be closed in practice by a plug or other suitable closure.

The blast nozzle 9 comprises a cylindrical body having at its inner end an angular head or flange 10 for the application of a 105 wrench, and provided at such end with a

threaded nipple 11 fitting within the threaded bore 7, said nipple being cored and internally threaded, as at 12, the axis of said core being arranged out of alignment with the axis of the nozzle body. The outer end of the nozzle is cored and internally threaded as at 13, to receive the threaded body 14 of a coupling member 15, said coupling member being provided at its outer end with an angular head for the application of a wrench. The threads of the core 13 terminate in rear of the inner end of a core, which is flared or beveled to provide a bowl-shaped blast chamber 17, centrally communicating with a blast bore or passage 18 extending axially through the nozzle body between the core 12 and chamber 17, the passage 18 being of the same diameter as the bore or passage of a blast tube 19, disposed and mounted as hereinafter fully described.

As shown, the blast tube 19 extends into the trap at a slight upward angle of inclination, thereby directing the sand practically longitudinally of the channel, and thus avoiding to a material extent the usual cutting of the trap body by the sand. The air blast is delivered through the coupling member 14 from a supply pipe 20 connected therewith to supply air to the receiving chamber 17, from which chamber it passes to and through the bore 18, thence to and through the bore or passage of a blast head 21, and finally through the blast tube 19, from which it issues into the channel 5, thereby feeding the sand with a required pressure into the sanding or delivery tube 4. The blast head 21 comprises an externally threaded body or plug which fits with the core 12 and is provided with an angular outer end 22 for the application of a wrench, such end of the plug being internally cored and threaded for the reception of the threaded rear end of the nozzle 19. The plug 22 is formed with a blast channel or passage constituting a part of the blast passage of the nozzle as a whole, the said passage in the plug having an inlet portion 23 an outlet portion 24 and an intermediate portion 25. The inlet portion 23 of the plug, which is arranged parallel with and above the axis of the plug, communicates with the passage 18, while the delivery portion 24 of the passage in the plug communicates at its forward end with the blast tube 19 and at its rear end with the intermediate channel portion 25. The portion 25 of the plug channel forms a jog or offset between the receiving and delivery portions 23 and 24 of such channel, and forms therewith a channel of zigzag-shape, the delivery portion of which inclines at an angle forwardly from a point below the axis of the plug and at its delivery end coincides with the axis 65 of the plug so as to be disposed substan-

tially in longitudinal alignment with the bore of the blast tube 19. The intermediate portion 25 of the blast passage of the plug channel is suitably closed at its upper end or above its point of intersection with the inlet end 23 at the point where it opens through the top of the plug, it being understood that the portions of the passage are formed by drilling the plug at the required angles. The portions 23, 24 and 25 of the plug passage are of uniform diameter, and it is evident that by reason of this shape of passage the portion 25 forms a trap to retard or prevent the backward passage of any particles of sand that may work back into the nozzle through the blast tube, so that they will be subsequently ejected by the blast to prevent clogging of the nozzle. While the irregular form of the passage may, under some conditions, slightly diminish the initial velocity of the blast, this is compensated for and overcome by the compression of the air in striking the forward wall of the portion 25 and then reacting or expanding, by which its pressure is increased within the portion 25 to clear the same of any particles of sand and the blast then passes with slightly reduced velocity and a tendency to expansion through the portion 24. The blast will thus be caused to issue through the nozzle with a proper volume and pressure proportioned to the diameter of the channel 5 to avoid objectionable concentration of the blast and delivery of the sand in an objectionably compact mass and under objectionable pressure. Therefore, the sand will be delivered in a fairly spread body under a comparatively low, but at the same time sufficient forcing pressure for delivery, so that the concentration of the blast and cut-away of the walls of the trap or delivery tube will be effectively avoided. A trap embodying my construction is accordingly adapted for long and continuous service.

It will be observed that the nozzle 9 is devoid of check valves or other elements liable to clog and render the nozzle inoperative, the zigzag or irregular form of that portion of the discharge passage within the head or plug 21 tending to prevent the passage of particles of sand backward thereinto beyond a certain point, so that the bore of the nozzle will be self clearing under all ordinary and normal conditions. It may sometimes happen, however, that small particles of sand will work back into the bore 18 from the jars and vibrations incident to the travel of the engine, and the chamber 17 is therefore provided to receive and trap these particles, as well as to serve as an expansion chamber. To effect the dislodgment of these particles and a self-clearing action of the nozzle, whereby it is at all times maintained in operative condition, the

threaded portion 14 of the coupling member 15 is formed to provide a blast rose or induction nozzle 26 having an annular series of jet orifices 27. These orifices extend from the bore of said coupling member to the chamber 17, which is of relatively greater diameter than said bore, at an outward angle of inclination, whereby currents of air issuing from the jet orifices are adapted to strike the curved wall of the bowl and produce a whirl or vortex, whereby the entrapped sand is taken out by the whirling column of air and carried therewith through the nozzle into the channel 5. Any retention of sand particles in the chamber 17 is thus prevented and the nozzle kept clear without the use of valves or other extraneous devices which are liable to bind, clog or to be otherwise rendered inoperative by particles of sand. Upon removing the nozzle from the opening 7 the channel may be cleaned out through said opening, as will be readily understood.

An auxiliary pressure channel 28 is formed in the body 1 and opens into the delivery end thereof beyond the delivery end of the sand channel 5, said pressure channel entering the body at a point adjacent its forward end, the entrance end 29 being internally threaded to receive the delivery end of a blast pipe 30, while the outlet 31 of said passage is interiorly threaded to receive the inlet end of a clearance blast tube 32 which extends into the entrance end 35 of the sanding or delivery tube 4. The tube 4 curves downwardly at its entrance end to dispose said tube at the proper delivery angle, and the tube 32 is similarly bent within the tube 4 so as to lie out of the path 40 of the sand delivered into said tube 4 by the blast nozzle. Through the channel 28 and tube 32 a blast of air may be delivered into the tube 4 to free said tube 4, whenever choked, from accumulated material, as will 45 be readily understood.

It will be seen from the foregoing that the present invention provides substantial improvements over my prior patented structure and obviates the necessity of employing 50 a shelf overhanging the delivery end of the nozzle and clearance channel or pocket beneath the delivery end of the nozzle, also the use of a check valve in the nozzle, while at the same time a free cleaning 55 out of the sand channel whenever required may be conveniently effected. It will, of course, be understood that the nozzle may be mounted and locked for adjustment to dispose the delivery end of the nozzle to 60 regulate the feeding effect of the blast on

the sand, as in my aforesaid patented structure.

I claim:

1. A sand trap formed with a sand channel, a blast pipe connected therewith, and 65 a blast nozzle communicating with said channel, said nozzle being provided with a bore arranged at an angle to the axis of the channel and having inlet and delivery portions arranged out of alinement with each 70 other but in parallel planes and an angular portion intersecting said inlet and delivery portions, said angular portion being approximately of V-form.

2. A sand trap formed with a sand channel, 75 a blast pipe connected therewith, and a blast nozzle communicating with said channel, said nozzle having a bore inclined to the axis of the channel, said bore having inlet and delivery portions which are 80 comparatively straight and extend in the same general direction as the channel and out of register but in parallel relation to each other, and a substantially V-shaped angular portion between the said 85 inlet and delivery ends of the channel, the arms of said V-shape portion respectively communicating with the inlet and delivery portions of the channel.

3. A sand trap formed with a sand channel, 90 a blast pipe, and a nozzle comprising a body provided with an air inlet, a blast tube having a discharge bore, and a plug fitted in said body and receiving said tube, said plug being provided with a bore having 95 portions communicating with the inlet passage in the cylindrical body and the bore of the blast tube, said passage being in part of V-form to provide a crooked portion in the length of the passage through the 100 nozzle.

4. A sand trap having a sand channel, and a blast nozzle provided with a passage having a crooked portion at a point in the length thereof, and means independent of 105 said crooked portion for producing a whirl in the line of the blast to clear said passage and trap.

5. A sand trap formed with a sand channel, and a blast nozzle having a channel 110 formed with a zigzag portion and whirl producing means at a point in rear of said zigzag portion.

In testimony whereof I affix my signature in presence of two witnesses.
